United States Patent Office

Des. 202,934
Patented Nov. 16, 1965

202,934

BOTTLE OR SIMILAR ARTICLE

Livingston C. Douglas, Leonia, N.J., assignor to Colgate-Palmolive Company, New York, N.Y., a corporation of Delaware

Filed July 30, 1964, Ser. No. 31,076

Term of patent 14 years

(Cl. D58—9)

FIG. 1

FIG. 2

FIG. 3

FIG. 4

FIG. 5

FIGURE 1 is a side elevational view of a bottle or similar article embodying my new design;

The side not shown is substantially a mirror image of the side shown in FIGURE 1.

The essential features of my design reside in the portions illustrated in solid lines.

I claim:

The ornamental design for a bottle or similar article, substantially as shown and described.
